UNITED STATES PATENT OFFICE.

HARRY L. HORNING, JAMES B. FISHER, AND ARTHUR W. POPE, JR., OF WAUKESHA, WISCONSIN, ASSIGNORS TO WAUKESHA MOTOR COMPANY, OF WAUKESHA, WISCONSIN, A CORPORATION OF WISCONSIN.

HEATER.

Application filed March 30, 1925. Serial No. 19,282.

This invention relates to an improved heater adaptable particularly for use in connection with explosive engines for controlling the temperature of the air before it reaches the air intake of the carburetor which supplies the engine with explosive mixtures. The object of the invention is to produce a simple construction which can be readily attached to the frame or exhaust manifold of an engine to receive the heat therefrom and to be either manually or automatically adjusted to efficiently control the temperature of the intake air so that the air will be properly heated while the engine is idling or working under light load and so that less heat will be applied to the air as the engine speed increases. Generally speaking, the heater comprises a direct cold air passageway and a shunt heated air passageway, together with a valve mechanism readily operable to shunt more or less of the air through the heated passageway and to shut off the heated passageway when the engine is at full speed or load. For automatic control, the valve structure will be automatically adjusted by the pressure of the air flowing directly through the direct air passage. The invention will be more fully understood by reference to the accompanying drawings, in which

Fig. 1 is a top elevational view with parts broken away;

Fig. 2 is a front elevational view with parts broken away; and

Fig. 3 is a sectional view on plane 3—3 of Fig. 2.

The heater body may be in the form of an integral casting and comprises the part 10 forming the direct air passageway 11, and the elongated part 12 extending at right angles from the part 10 and forming the heater section. The part 10 is shown of circular cross section and the part 12 of rectangular cross section. The front of the heating section is closed by the wall 13, but the rear side of the part 12 is open and has the peripheral seating flange 14 by means of which it may be seated against a heating surface, such as the wall 15 of the exhaust manifold of an explosive engine. Running longitudinally in the part 12 along a median plane is the partition 16 which extends from the passageway 11 up to within a short distance of the opposite end of the part 12, so as to form the incoming and outgoing air passageways 17 and 18. The structure may be detachably secured to the supporting wall 15 by means of screws 19, the heat from the heated wall then extending into the passageways 17 and 18 and heating the air flowing therethrough.

Extending transversely through the structure at the juncture of the parts 10 and 12 is the spindle 19. This spindle is journaled in the front lug 20 and the rear wall section 21, and at its front end is deflected to form the lever arm 22 on which a weight 23 is adjustable. The spindle 19 extends along the end of the partition 16, and secured on the spindle is the valve plate 24, which is of rectangular shape to fit between the walls 13 and 21, and at its outer end is semicircular to fit the outer walls of the cylindrical section 10. The weight 23 tends to swing the spindle structure to normal position with the inner part of the valve plate extending longitudinally and against the top of the partition 16, and with the outer end of the plate transversely across the passageway 11 and against a stop projection 25. This is the normal or one extreme position of the valve plate. In its other extreme position, it will be vertical and in position in front of the ends of the passageways 17 and 18 to shut these passageways off from the direct air passageway 11. The dotted lines show this extreme position of the valve plate and of the weighted lever.

In practice, the lower end of the part 10 is connected by a conduit 26 with the air intake of the carburetor for the engine to which the heater is applied, such air intake delivering air for the explosive mixture within the carbureting chamber which, under control of a throttle valve, is connected with the fuel intake of the engine.

As before stated, the action of the weight 23 tends to keep the valve plate in position to close the direct passageway 11 so that when the throttle valve at the carburetor is in position to permit only limited suction effort at the carburetor air intake and consequently at the lower end of the passageway 11 of the heater, the suction will not be sufficient to pull down the valve plate 24 against the weight 23 and the supply air flowing into the top of the passageway 11 above the valve plate will circulate through

the heated passageways 17 and 18 before reaching the conduit 26 leading to the carburetor air intake, and the air is thus heated. When the suction is low the velocity of the air flow is also low, and consequently the air has a chance to be highly heated before it reaches the carburetor to mix with the fuel to form the explosion mixture. Thus, when the engine is idling a hot mixture is assured. As the throttle is gradually opened wider and the engine increases in speed, the suction in the passageway 11 below the valve plate will correspondingly increase, as also the velocity with which the incoming air strikes against the valve plate. The effect of the weight 23 is then soon overcome and the valve plate will respond to the suction and velocity to swing and to open the direct passageway 11 and close off the entrance into the passageway 16. The valve plate thus automatically assumes various degrees of opening, depending upon the suction and the velocity, and when the engine gets up to full speed the valve plate will be in or close to extreme position in which it shuts off the hot passageways and causes unheated air to flow directly through the passageway 11 and to the carburetor, the temperature of the carburetor mixture varying accordingly, it being hot for idling operation of the engine and cold when the engine is running at speed. In other words, the engine is supplied with heated air with a gradually diminishing temperature until it is up to speed and will operate satisfactorily with cold air fed to the carburetor.

It is desirable to have a hot mixture under suddenly increased speed or acceleration of the engine. When the throttle is suddenly opened for acceleration, the heater valve, on account of inertia, will not immediately respond to the increased suction, and during such inactive period a goodly supply of highly heated air will be drawn into the carburetor for a good hot mixture. The heater valve will then respond and automatically adjust for the proper and efficient heating of the air. The structure shown thus automatically insures the proper carburetor mixture for different conditions of operation of the engine.

Instead of the automatic control shown, the heater valve can be positively operated by a suitable connection to the lever 22. There could also be a connection between the carburetor throttle lever and the heater lever 22 so that adjustment of the throttle will automatically effect proper control of the heater. Other modifications of construction and control are possible, all of which will still come within the scope of the invention.

We claim as follows:

1. The combination with an explosive engine and a carburetor for supplying the explosive mixture therefor, of an air tempering

structure supported at the engine and having an inlet and an outlet, said outlet being connected with the air intake of the carburetor, an unheated direct passageway through said structure between said inlet and outlet, a heated passageway through said structures subjected to the heat of the engine whereby air traveling through said passageway will be heated, a valve structure movable to one extreme position of closure of the unheated passageway and opening of the heated passageway and to another extreme position of opening of the unheated passageway and closure of the heated passageway, yielding means tending to hold said valve structure in the first mentioned extreme position, said valve structure being subjected in said unheated passageway to the pressure of the air flowing therethrough and said pressure tending to move said valve structure to the other extreme position, said pressure and yielding means cooperating to hold said valve structure in extreme or intermediate position, depending upon the suction effect transmitted from said carburetor to said structure outlet.

2. In a stove structure for tempering the intake air of a carburetor, the combination of a direct unheated air passageway, said direct passageway having an air inlet and having an air outlet adapted for connection with the air intake of a carburetor, a heated passageway having its ends communicating with said air inlet and outlet respectively, and a valve structure operable to close said direct passageway and open both ends of said heated passageway and adapted to open such direct passageway and close both ends of said heated passageway.

3. In a stove structure for tempering the intake air of a carburetor, the combination of a direct unheated air passageway, said direct passageway having an air inlet and having an air outlet adapted for connection with the air intake of a carburetor, a heated passageway extending between said inlet and said outlet, a valve structure for said passageways, means tending to hold said valve structure in position to close said direct passageway and open the unheated passageway to the flow of air, said valve structure being responsive to the pressure of the air flowing from said inlet to said outlet to increase the passageway through said direct passageway and to positively restrict the flow through said heated passageway.

4. In a stove structure for tempering the intake air of a carburetor, the combination of a direct unheated air passageway, said direct passageway having an air inlet and having an air outlet adapted for connection with the air intake of a carburetor, a heated passageway having an air inlet and an air outlet communicating with said direct passageway, a valve structure at the juncture

of said direct passageway and the inlet and outlet ends of said heated passageway, said valve structure being operable to close said direct passageway and to expose the ends of said heated passageway when in one position, and adapted to open said direct passageway and to close the ends of said heated passageway when in another position, and adapted to control the partial opening through said direct passageway and at said heated passageway ends when in intermediate positions.

In witness whereof, we hereunto subscribe our names this 27 day of March, 1925.
